MAGAZINE RACK

Maurice Duchin, New York, N. Y.

Application March 16, 1955, Serial No. 35,063

Term of patent 7 years

(CL. D33—2)

FIG. 3.

FIG. 2.

FIG. 1.

I claim:

The ornamental design for a magazine rack, as shown.
